RESILIENT BALL FOR A TWIRLING BATON

John F. Hale, 3729 Greenbay Drive 45415, and
Frederick J. Miller, 2150 E. Rahn Road 45440, both
of Dayton, Ohio

Filed May 21, 1971, Ser. No. 145,997

Term of patent 14 years

Int. Cl. D21—01

U.S. Cl. D34—5 BC

FIG-1

FIG-2

FIG-3

FIG-4

FIG. 1 is a perspective view of the resilient ball for a twirling baton of our new design;

FIG. 2 is a side elevation of said new design;

FIG. 3 is a right end elevation thereof; and

FIG. 4 is a left end elevation thereof.

We claim:

The ornamental design of a resilient ball for a twirling baton, substantially as shown.
